SUCTION CLEANER

Charles H. Sparklin, Chicago, Ill., assignor to
 Birtman Electric Company, Chicago, Ill., a corporation of Illinois

Application October 7, 1935, Serial No. 43,953

8 Claims. (Cl. 15—16)

This invention relates to improvements in suction cleaners and more especially to that type of cleaner provided with a nozzle that is vertically adjustable with respect to the surface of the material being cleaned.

It is well known that suction cleaners of the type here under consideration are most generally used for cleaning rugs, carpets and the like although, of course, they are also used for cleaning bare hardwood floors, linoleum and other surfaces. In connection with the cleaning of carpets, however, materials of varying thickness and softness are encountered; and consequently it has been found advisable to provide the cleaner with a vertically adjustable nozzle so that when operating on a carpet that is relatively thick and soft where the wheels sink in to a relatively great extent, the nozzle can be vertically adjusted upwardly so that in the cleaning of such carpet the mouth of the nozzle will not be too close to the fabric or bear too much thereon. Contrariwise, when operating upon a thin hard carpet or on a bare floor, or linoleum, or the like, where the wheels do not sink in to any perceptible extent, it has been found advisable to adjust the nozzle vertically downwardly so that it will be in proper position with respect to the surface being cleaned. Likewise, in operating upon carpets of this thickness it has been found that vertical adjustment of the nozzle is necessary or desirable.

The principal feature of my invention is the provision of indicating means enabling the operator readily and quickly to determine the proper adjustment of the nozzle.

In general, it may be stated that this is accomplished by providing a pilot in the nature of a relatively light member that will "float" on the surface of the material being cleaned. One or more of the wheels of the cleaner, however, will sink into the material to a certain extent below its surface, depending upon the nature of the material itself. This sink of the wheels is shown by an indicator on the cleaner and the operator can easily adjust the nozzle accordingly. For convenience, there may be another indicator to show the height of the nozzle, and the two indicators may be so calibrated that all that is necessary is for the operator to bring the two arrows into registry to obtain the proper height of the nozzle on any material being cleaned.

Other features and advantages of my invention will appear more fully as I proceed with my specification.

In those forms of devices embodying the fea-

tures of my invention shown in the accompanying drawings—

Fig. 1 is a view partly in side elevation and partly in section; Fig. 2 is a fragmentary top plan view; Fig. 3 is a bottom plan view; Fig. 4 is a segmentary view on an enlarged scale, partly in front elevation and partly in section; and Fig. 5 is a view in perspective of the pilot member and the adjacent wheel.

Cleaners with vertically adjustable nozzles of various types have heretofore been made in which means are provided for vertically adjusting the nozzle with respect to the carriage depending upon the thickness, character and type of surface being cleaned. Various means have been provided also for manually effecting such adjustment. It is to be understood that my invention may be used in virtually any form of such cleaner. That is, the particular means provided for adjusting the nozzle may have a variety of forms. The principal feature of my invention is the provision of means for visually indicating to the operator the extent to which the nozzle shall be adjusted.

As shown in the drawings, the cleaner may be of a conventional type supported by two front wheels 10, 10' and two rear wheels 11, 11'. The nozzle is indicated by 12. As here shown vertical adjustment of the nozzle is effected by raising or lowering the rear wheels 11, 11'. This pivots the entire cleaner on the axis 13 of the front wheels 10 to raise or lower the mouth 12a of the nozzle 12. As here shown adjustment of the rear wheels 11 is effected by means of the screw 14 operating in the lug 15 on the cleaner. The lower end of the screw 14 has a ball and socket joint 16 with sufficient play so that rotation of the screw by means of the handle 17 will adjust the back wheels 11 upwardly or downwardly as desired; thus giving the desired elevation of the nozzle 12.

18 may indicate a ball chain with one end connected to the arm 19 carrying one of the rear wheels 11, said arm being pivoted at 20. The other end of the ball chain 18 is wrapped around a spring pressed shaft 21 carrying the indicating arrow 22 operating in connection with a scale 23 so that the arrow 22, by reference to suitable markings or calibrations on the scale 23, will always show the vertical adjustment of the nozzle 12.

I shall now describe the pilot member utilized for indicating the degree of sink of one of the wheels. It is preferable, of course, to measure or indicate the sink of one of the front wheels since they ordinarily carry more weight than the rear wheels. It is also desirable to place the pilot in

close proximity to one of these front wheels as this will give a truer indication of the actual sink of the wheel into the material below its surface. One of the wheels and the pilot member or float 5 is shown in perspective in Fig. 5. 10 indicates the wheel, the pilot member being in the shape of a cylindrical shell of light, thin sheet metal indicated by 25. This shell is pivoted at 26 in the fork 27 carried by the cleaner and has a portion 10 cut away as indicated at 28 to accommodate the support 29 for the wheel 10. The pilot is large enough so that it is free to move up and down relative to the wheel. 30 indicates a light spring preferably employed to hold the pilot 25 down on 15 the surface of the material being cleaned. This spring is very light, however, and the pilot itself is very light in weight so that it will "float" substantially on the surface of the material being cleaned. That is, it will sink into the material 20 only to a very small extent, if at all; and not nearly as much into soft material as the wheel 10 will sink. It is to be noted also that the lower surface of the pilot 25 as indicated by 25 being cylindrically curved will slide easily over the 25 surface of the material being cleaned with little or no tendency to sink down into such surface. It will be seen also that the lower edge of the pilot that bears on the surface being cleaned has considerable width, thus giving at least a line 30 contact of considerable length and in all probability a surface contact of considerable area, thus preventing the pilot from sinking into the surface of even soft thick carpets to any perceptible extent. As here shown, the spring 30 is connected to an ear 31 on the pilot at one end, the other end of the spring being connected to a suitable lug 32 carried by the cleaner.

The pilot 25 is provided with an ear 33 to which is pivotally connected the bar 34, the rear end of 40 which is pivotally connected to a member 35 rotatably mounted on the shaft 21 which carries the indicating member 22. The member 35 carries another indicating member 36 which shows the vertical movement of the pilot 25 with respect to 45 the wheel 10. The operation of the pilot is shown in Fig. 4 where a rather thick soft carpet is indicated by 37. That is, the carpet has a rather thick pile. It will be seen that the wheel 10 is sinking into the carpet below its surface to a considerable extent while the pilot 25 is riding or floating substantially on the surface. By surface, is meant the very top of the fabric. Thus the pilot 25 is resting substantially on the upper ends of the threads forming the pile without bending them over or crushing them down to any considerable extent. As stated, however, the wheel 10 sinks down into the carpet below its topmost 50 surface to a considerable extent and the extent of this sink of the wheel 10 is indicated by the position of the indicator 36 with respect to the scale 23. Since there is a substantially correct setting for the nozzle for each degree of sink of the wheel

10 the operator, by looking at the position of the indicator 36, can tell how to adjust the nozzle. Since the adjustment of the nozzle is indicated by the pointer 22, he can readily determine when he gets the correct adjustment. If desired, the indicators 36 and 22 may be so positioned and proportioned and the scale 23 so calibrated that the correct position of the nozzle will be obtained in each case when the pointer 22 is brought into registry with the pointer 36. This will save the 10 operator the trouble of doing any calculating or integrating in adjusting the nozzle and will provide a very effective, efficient and quick means for indicating to the operator the proper vertical adjustment of the nozzle for each kind of material 15 being cleaned. For the purpose of clarity in the drawings, the indicators 22 and 36 are not in registry.

While I have shown and described certain embodiments of my invention, it is to be understood 20 that it is capable of many modifications. Changes, therefore, in the construction and arrangement may be made without departing from the spirit and scope of the invention as disclosed in the appended claims, in which it is my intention to 25 claim all novelty inherent in the invention as broadly as permissible, in view of the prior art.

What I claim as new, and desire to secure by Letters Patent, is:

1. In a suction cleaner having supporting 30 wheels, a pilot adapted to float substantially on the surface of the material being cleaned, and means operated by said pilot for indicating the degree of sink of one of said wheels into said material below its surface. 35
2. In a suction cleaner having supporting wheels, a pilot adjacent one of said wheels adapted to float substantially on the surface of the material being cleaned, and means operated by said pilot for indicating the degree of sink of said wheel 40 into said surface. 45
3. Apparatus as claimed in claim 1, in which the pilot is provided with a curved lower surface.
4. Apparatus as claimed in claim 2, in which the pilot is provided with a curved lower surface. 45
5. Apparatus as claimed in claim 1, in which the pilot is substantially cylindrical.
6. Apparatus as claimed in claim 2, in which the pilot is substantially cylindrical and partially surrounds said wheel. 50
7. In a suction cleaner having supporting wheels, a pilot adapted to float substantially on the surface of the material being cleaned, a movable visual indicator, and a connection between said indicator and said pilot. 55
8. In a suction cleaner having supporting wheels, a pilot adjacent one of said wheels adapted to float substantially on the surface of the material being cleaned, a movable visual indicator, and a connection between said indicator and said pilot. 55

CHARLES H. SPARKLIN.
